UNITED STATES PATENT OFFICE.

EDWARD S. MARSHALL, OF ST. LOUIS, MISSOURI, ASSIGNOR TO THE WESTERN RAILWAY EQUIPMENT COMPANY, OF EAST ST. LOUIS, ILLINOIS.

DESIGN FOR A DRAFT-LUG AND DRAW-BAR FOLLOWER.

SPECIFICATION forming part of Design No. 26,470, dated December 29, 1896.

Application filed November 23, 1896. Serial No. 613,205. Term of patent 14 years.

To all whom it may concern.

Be it known that I, EDWARD S. MARSHALL, a citizen of the United States, residing at the city of St. Louis, State of Missouri, have invented a certain new and original Design for a Draft-Lug and Draw-Bar Follower, of which the following is a full, clear, and exact description, reference being had to the accompanying drawings, forming a part of this specification, wherein—

Figure 1 is a top plan view. Fig. 2 is a front elevational view. Fig. 3 is a side elevational view. Fig. 4 is a rear elevational view. Fig. 5 is a sectional view taken on a horizontal plane.

This invention relates to a new and original design for a draft-lug and draw-bar follower; and it consists in the shape and configuration illustrated in the drawings and hereinafter fully described.

In the drawings, A indicates the front wall, which is plain, and is formed with an opening a at or about its center.

B indicates the side walls, which are formed with vertically-disposed projections or ribs b at their forward ends, the forward or outer faces of the projections being on a plane with the outer face of the front wall A, while between the rear ends of the walls and the projections the walls are formed with openings or perforations b' .

C and D indicate the top and bottom walls,

respectively, which are cut away from the rear, as shown. The top wall C has a T-shaped projection c at its forward end, the front face 35 of the cross of the T being on the same plane with the outer face of the front wall A. This T is highest at the junction of the cross and stem, the cross gradually falling to the plane of the top wall in a curved line, while the stem 40 gradually falls in a straight line.

The rear end is open at its center the width of the cut-away portions of the top and bottom walls, while two wings E connect the rear ends of the top, bottom, and side walls on each 45 side of the opening.

An inwardly-projecting flange or ring a' surrounds the opening a on the inner face of the front wall. Webs F radiate from this ring to the top, bottom, and side walls, the horizontal webs also jointing the wings E, the free edges of said horizontal webs being fancifully curved, as shown.

What I claim is—

The design for a draft-lug and draw-bar follower, substantially as herein shown and described.

In testimony whereof I hereunto affix my signature, in presence of two witnesses, this 18th day of November, 1896.

EDWARD S. MARSHALL.
